(57) **CLAIM**

The ornamental design for a bowl, as shown and described.

DESCRIPTION

FIG. 1 is a perspective view of a bowl showing the claimed design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.

The broken lines illustrate portions of the bowl that form no part of the claimed design.
